J. R. Campbell.

Drying Dress.

Patented Nov. 30, 1835.

John D. Campbell, of Boston, Mass.
Letters Patent.

The subscriber referred to in these Letters Patent, and making part
of the same, doth humblye represent in the words of the said John
Campbell himself of his improvement in the Flying Draf.

It will be known that the aforesaid John Campbell, of Boston in the County of Suffolk and State
of Massachusetts, have invented a new and useful improvement
in the flying Draf, and that the following is a full and exact de-
scription of the construction and operation of said improvement,
as invented by me, it being understood that it is an improve-
ment on the draft or suit already patented by Nathaniel Hol-
well of Sidney in the County of Delaware and State of New-
York, on the twentieth day of April 1834, under the title
of a flying Suit, which patent is all its right and title now
assigned over to me the thirteenth day of July 1835, and duly
recorded August 4th 1835, in the Patent Office.

The part on which I improve is the covering for the head, and
to effect this I throw off the Indian Rubber or Gum Elastic
of which the cap as well as the rest of the draft is composed, and
substitute in its place a cap of Glass, that there may be an
uninterrupted manner of going around the dove not provided
for in the old suit and this will be the means of preventing
the risk of fatal accidents from entangling of the cords, or
ropes attached to the dove and also from other con-
cess. The cap of Glass is to descend as low down the face
as desired, say to within a short distance of the shoulder
where it will be united to a copper band which will then
after descending some short distance below said junction, turn
out again by a rectangular lip sufficiently protuberant to fill
up the opening which is left where the Rubber cap was dis-
placed and which must be large enough to allow the body

to water the draft, feet foremost. This size of the opening is necessary as the cloth cannot with safety to the diver be fastened or gathered up around the same, because to join the two, that is, the cloth and the vine so as to be water tight, a groove is made all round the vine ~~and~~ ^{and} on the circumference thereof and the cloth being brought above it, another circular and rounded hoop is clasped tightly on so as to fill up the groove, and therein retains the cloth firmly to prevent leakage. At the upper band beneath the junction with the flap is formed a round hole to be closed with a screw cap so as that it may be removed, at pleasure or according to the top of the water, so as to be able to come through the opening, and open side of it and to be formed like holes ~~one~~ ^{one} ~~and~~ ^{and} ~~the other~~ ^{the other} ~~one~~ ^{one} above the other, the top one is intended to receive the end of a flexible tube to be screwed fast into it, which tube has the other end left open and dangling in the water, for the purpose of allowing the impure air to escape. It is also used as a regulator for all that类 of fluids, by which they seek a level as is demonstrated in the junction of two pipes, one large and the other small. wherein the fluid will stand at the same height in each. so with the regulator for as it is - sisted by the arm of the diver, so will be the corresponding rise in the air contained in the drops, and as he will then have it left inflated, he will sink should he depress the end of the tube, then the air in the drops will descend to water, flat it and he will consequently rise. Beneath the draft is added cylindrical case of metal which the diver occupies by passing into its open and lower end, so that his head shall project from the upper one, which is open also and affords his shoulders one hole for his arms to pass through, the whole case of course resting on these points on his shoulders. It descends to about his hips and therefore presents no encumbrance to his legs, nor to his arms which are thus at perfect

leberty. It is also furnished with a joint on the centre of the cylinder to 25 to allow a motion forward or to stoop. This is to prevent accident from the sudden extraction of the air but the Body might be comfortable. The lower tube hole has its tube screwed into it the other end of which rises to the top of the water and there receives the air by compression from an air pump or other contrivance.

What I claim as my invention and for which I now apply for Letters Patent is the combination of the cap of Blaftz with the Rubber dress and the use of the metal Cylinder according to the plan set forth. In testimony that the above is a full description of the construction and use of my improvement. I have hereunto set my hand this tenth day of November Eighteen Hundred and thirty five
